UNITED STATES PATENT OFFICE.

ARCHIBALD D. EVANS, OF NEW CASTLE, PENNSYLVANIA.

PACKAGE.

Application filed July 17, 1926. Serial No. 123,213.

This invention relates to packages, and more particularly to a novel form of package adapted for packaging tin plate or other heavy articles, although its use is not confined thereto.

One object of this invention is to provide a package having maximum strength and minimum weight, and which may be readily applied to the articles being packaged by a minimum of labor.

Another object is to provide a one-piece package blank which may be readily folded around the articles to be packaged.

A further object is to provide a package having the novel design, construction and combination of parts hereinafter described and illustrated in the accompanying drawings.

In the drawings:

20 Figure 1 is a plan of a blank from which the package of this invention is made.

Figure 2 is a perspective view of a partly assembled package of tin plate.

25 Figure 3 is a similar view of a completed package.

Referring more particularly to the drawings, the letter A designates the blank as a whole, which is of rectangular shape and composed of fiber, paper board, sheet metal 30 or the like.

In order to form a package or box from the blank, two pairs of weakening or score lines 2 and 3, and 4 and 5, respectively, are formed longitudinally of the blank, each 35 pair being spaced from the longitudinal center line. Two other pairs of weakening or score lines 6 and 7 and 8 and 9, respectively, are formed transversely of the blank, each pair being spaced from the transverse 40 center line of the blank. The inner lines 2, 4, 6 and 8 of the pairs of lines, define the edges of the bottom 10 of the package, while the portions of the blank between the lines 2 and 3, and 4 and 5 form the side walls 12 45 of the package, and the portions of the blank between the lines 6 and 7, and 8 and 9 form the end walls 13 of the package.

The blank is slit or cut through along the lines 7 and 9 inwardly from the outer edge 50 to the inner lines 2 and 4, as at 14, and also along the lines 2 and 3, and 4 and 5 between the lines 6 and 7, and 8 and 9, as at 15, so as to form end flaps 16 and 17.

55 The portion of the blank beyond the transverse lines 7 and 9 forms combined reinforcing and binding flaps 18, while the

portions of the blank beyond the side lines 3 and 5 and between the lines 6 and 8 form top sections 19 and 20.

In order to assemble the blank to form a package it is only necessary to fold the blank on the weakened or score lines, so as to enclose the material. If it is desired to package tin plate, a stack of tin plate will be assembled and laid on the bottom 10 of the wrapper, the side walls 12 are then folded or bent upwardly into vertical position, and the top sections 19 and 20 are then folded or bent over the top of the plate. The end flaps 17 are then bent down along the ends of the plate and the end flaps 16 are bent inwardly over the flaps 17. The end portions of the blank are then bent upwardly along the ends of the plate so as to overlie the flaps 16 and 17, thereby forming the body portion of the package. The flaps 18 are bent downwardly so as to overlie the top sections 20 and the ends of the flaps 18 are then bent around the package forming an encompassing, reinforcing and binding portion.

The flaps 18 may be either glued in position to hold the package in assembled portion, or they may be held in position by metal straps or bands 22 having their ends 55 spot-welded together, as shown in the drawings at 22a. It will be understood, of course, that if desired, the flaps 18 may be glued and the straps 22 also added.

A plurality of holes 23 are preferably 90 formed in the side walls 12 to permit the escape of air from the package when the loaded packages are compressed by piling or handling, so as to prevent the air breaking the package.

95 It will be readily appreciated by those skilled in the art, that I have provided a package or box having great strength, and that may be readily and cheaply assembled around the material to be packaged.

100 While I have described one specific embodiment of my invention, it will be understood that I do not wish to be limited thereto, since various modifications may be made without departing from the scope of my invention as defined in the appended claims.

1 claim:

110 1. A one-piece wrapper for tin plate and the like, comprising a bottom wall, side walls formed integral with said bottom wall, sections of approximately equal width formed integral with said side walls and

2
adapted to form the top of said wrapper, end flaps formed integral with said top wall sections, other end flaps formed integral with said side walls and overlying said first mentioned end flaps, end wall members formed integral with said bottom wall, and combined reinforcing and binding flaps formed integral with said end walls and adapted to encompass the top, side and bottom walls of the body portion of said wrapper.

2. A wrapper blank, comprising a substantially rectangular piece of flexible material having two pairs of parallel score lines spaced apart and extending longitudinally of said blank, and two other pairs of score lines extending transversely of said blank and crossing said first named score lines, the portion of the blank bounded by the inner ones of said pairs of score lines forming the bottom portion of the wrapper, the portions of the blank between said first named pairs of score lines and terminating at the inner lines of said second named pairs of score lines forming the sides of the wrapper, the portions of the blank between said second named pairs of score lines and terminating at the inner lines of said first named pairs of score lines forming the end walls of the wrapper, the portions of the blank beyond the outer lines of said first named pairs of

score lines forming top sections of the wrapper, said blank being separated along the outer lines of said second named pairs of score lines inwardly to the inner lines of said first named pairs of score lines, and also separated along both of said first named pairs of score lines for the distance between said second named pairs of score lines, said separations forming end flaps, and the portions of said blank beyond the outer lines of said second named pairs of score lines forming combined reinforcing and binding flaps.

3. A wrapper blank, comprising a substantially rectangular piece of flexible material having two pairs of parallel score lines spaced apart and extending longitudinally of said blank, and two other pairs of score lines extending transversely of said blank and crossing said first named score lines, and said blank being separated inwardly along the outer lines of said second named pairs of score lines to the inner lines of said first named pairs of score lines, and also separated along both of said first named pairs of score lines for the distance between said second named pairs of score lines to facilitate said folding.

In testimony whereof, I have hereunto signed my name.

ARCHIBALD D. EVANS.
